CODE CONVERTER

James A. Spencer, Teaneck, N. J., assignor to
 Radio Corporation of America, a corporation
 of Delaware

Application August 27, 1947, Serial No. 770,851

6 Claims. (Cl. 178—92)

1

The present invention relates to telegraph apparatus and more particularly to a device for converting telegraph signalling codes of one characteristic into a code having different characteristics.

In wire, cable and telegraph signals, messages are frequently received in printer code signals and retransmitted in cable or Morse code signals. Many devices for effecting code conversion have heretofore been developed but most of these are either too slow acting for commercial usage or require special operating procedures.

An object of the present invention, therefore, is the provision of a code converter overcoming the above-mentioned disadvantages.

Another object of the present invention is to produce a code converter device capable of accomplishing the conversion at a high rate of speed.

Another object of the present invention is the provision of a code converter operating to convert printer code or five unit signals into cable or Morse code signals without requiring special operating procedures. Printer codes are generally identical for upper and lower case characters associated with a particular type bar. Differentiation between upper and lower case characters is accomplished by preceding a character requiring a change in case by a case shift code group. In Morse and cable code upper and lower case characters are transmitted and received in entirely different character formations. These code characters differ in length and number of element units.

Still another object is the provision of a code converter mechanism which inherently provides a considerable overlap between the selecting and perforating operations whereby improved operating characteristics are obtained.

Briefly, the present invention includes a selector mechanism for receiving and translating incoming printer code impulses representative of message characters, all characters having the same total number of elemental units, into mechanical movements of code bars and a translating mechanism actuated by the mechanical movement of the code bars to so actuate a perforating mechanism that a tape is punched with a predetermined pattern to represent in Morse code the same characters, all in a proper time relationship to the received signal. The number of elemental units representing said characters may vary considerably.

The present invention will be more fully understood by reference to the following detailed de-

2

scription which is accompanied by a drawing in which:

Figure 1 shows in perspective a general view of an embodiment of the present invention;

Figure 2 illustrates in perspective a fragmentary portion of Figure 1 with only so much of the selector mechanism shown as is necessary for following the cycle of operations;

Figure 3 is an end view of Figure 1;

Figure 4 is the top view of the selector mechanism at the right hand end of Figure 1;

Figure 5 is an intermediate section taken midway of the code translating mechanism of Figure 2;

Figure 6 is a top view of the perforating mechanism at the left hand of Figure 1, and

Figure 7 is a detailed view of a portion of the case shift mechanism of the present invention.

Referring now to Figure 1 there is shown 20 mounted on base B, a code selector mechanism S, a converter arrangement C and a tape punching apparatus P. The selector S is generally an adaptation of sword and lever selector mechanisms such as used in teleprinters and is similar 25 to the selector mechanism shown in Morton Patent 1,745,633, granted February 4, 1930. The selector mechanism is fragmentarily shown in Figure 2 and in more detail in Figures 3 and 4.

The selector mechanism includes a pair of magnets 10 connected to the incoming telegraph line and responsive to printer code signals carried by the incoming line. The magnets 10 actuate an armature 12 having thereon an extension carrying a pair of parallel arms 13 and 14 (Fig. 2). The armature 12 is variably positioned to either the right or left (Fig. 2) in dependence upon whether a marking or spacing signal is being received. Thus, either of the parallel arms 13 and 14, but not both, is brought into alignment with the ends 23 and 24 of the swords 16. During the entire period of time when signals are to be received, motor M is operating driving shaft 20 through worm 21 on the motor shaft and worm wheel 22 on shaft 20. Mounted on shaft 20 and driven thereby through a clutch 25 is a selector cam sleeve 26 carrying individual cams 27, one for each of the five selector levers 28 associated with the swords 16. A stop arm is provided, which normally holds the selector cam sleeve stationary until released by the first spacing impulse per code character received by magnets 10. This structure is not shown in detail since it of itself forms no part of the present invention.

Now if it is assumed that a train of code impulses is being received and that the stop arm

has been just released, the selector cam sleeve will rotate in synchronism with the incoming code characters. As the individual code elements arrive at magnet 10, the armature will be either attracted or released in accordance with the marking and spacing elements of the code. The armature extension arms 13 and 14 will be brought into alignment with the ends 23 and 24 of the swords 16. The individual cam elements 27 carried in cam sleeve 26 actuate selector lever 28 in sequence drawing swords 16 down so that either end 23 or 24 of each sword is brought into engagement with arms 13 or 14. Thus the swords 16 are variably positioned to the right or left (Fig. 2) in accordance with the individual code elements of a code character. As the swords are released by the cam follower of each selector lever 28 falling off the toe of each of the cams 27, springs 30 cause the upper ends of swords 16 to engage one end or the other of T bars 32. The feet of T bars 32 are coupled to individual permutation bars 33, one for each of the five elements of each incoming code character. The permutation bars 33 are provided with notches 34 along their upper edges. For every received code combination, there is one position along the length of permutation bars 33 where all of the notches will be lined up, thus permitting one of the cross bars 25 to drop into the aligned notches. After the train of code impulses, representing one character, is received, a projection (not shown) on the cam sleeve assembly causes a clutch release member 35 to disengage a stop finger 36 on clutch sleeve member 38 and the teeth on clutch sleeve member 38 to engage similar teeth on a cooperating clutch member 39. Thus the gear train including spur gears 40, 41, 42 and 43 and skew gears 44 and 45 cause cam shaft 46 to be driven through one revolution. After the completion of one revolution the stop finger 36 engages the cam surface 36' causing the teeth on clutch sleeve member 38 to disengage the cooperating clutch member 39 and stop gear 40 and cam shaft 43. Cam shaft 46 carries a number of similar cams 47 which, in rotating, allow bail 48 to lower, permitting one of the cross bars 25 under the influence of its associated spring 54, to enter the slot existing in the permutation bar assembly (33). Associated with each of the cross bars 25 is a L-shaped bar 53 coupled with said cross bar by a hook 55 and a spring 56. Thus, each of the cross bars may lift, if necessary, without lifting the associated L-shaped bar if it is being held down. As the selected L bar is moved downwardly, it enters slots in perforator control bar assemblies comprising perforator bars 61 and space bars 62. These control bars are so notched that the perforator bars 61, representative of the dots and dashes in the Morse code for the selected letter are held against longitudinal movement by the selected L bar while the others are free to move. Also, that one of the spacing bars 62, which is representative of the length of the code combination to be punched, is locked against longitudinal movements.

Now, as the cam shaft 46 continues its rotation, all of the cross bars 25 are lifted, the selected one of the L-shaped bars 53 being held down by the pressure of control bars 61 and 62 consequent to the tape punching operation which will later be described. Thus, an overlap is provided between the selecting and perforating mechanisms.

It should be noted that, in the five element code, each code combination is representative of one letter and one upper case character such as

a numeral or punctuation mark. The selection between these two characters depends upon which of two case shift characters has last been transmitted. On the other hand, each letter and each upper case character in Morse code has its own individual code combination. Some means must be provided to accomplish this transformation. Therefore, I have provided a sixth permutation or case shift bar 33' aligned with the code element permutation bars 33 but not actuated by a T bar or sword.

When permutation bars 33 are so selected as to correspond to a case shift signal one of the two extra cross bars, case shift cross bars 25A or 25B, drops into aligned slots in code bars 33 when bail 48 is lowered. This actuates toggle lever 70 to one position or another, shifting sixth permutation or case shift bar 33' to one extreme or the other. Case shift bar 33' is so notched that only one of the cross bars 25, of the two selected by the remaining permutation bars 33, drops, depending upon whether a letter character or upper case character is desired. The toggle lever 70 is shown in more detail in Figure 7 where the covering plate 71 is shown in phantom. Toggle lever 70 has an inwardly depending arm 72 engaging in aperture 73 in code bar 33', for moving the bar by the action of the toggle lever. Spring 74 provides the toggle action, and maintains the lever 70 in one of its two extreme positions, where stop pin 75 is against an edge of aperture 76, formed by the punching out from the body of the lever, of arm 72.

The tape punching mechanism P includes a punch block 100 having holes therein adapted to cooperate with twenty code element punches 101, one individual to each control bar 61 and ten paper feed hole punches. The punching operation takes place by the punch block 100 being moved back against the punches, those of the punches 101 which are held stationary by the blocked control bars 61 punching holes in the tape while the paper presses the other back freely against the pressure of restoring springs 105.

The punching operation is initiated by the lowering of bail 48 by cams 47, rocking trip rod 106 through the crank 95 and connecting rod 96 (Fig. 5). The rocking motion of trip rod 106 causes lever 107 to release clutch 108, thus permitting motor M' to rotate cam shaft 109. Cam shaft 109 is provided with three cams 110, 120, 130. Cam 120 operates push rod 121 which moves restoring plate 122 away from the end of control bars 61, 62 so that any bars not blocked by L-shaped levers 53 may be moved back by the action of punch block 100.

Cam 130 moves punch block 100 against the punch pins on the ends of control bars 61 through cam follower 131. This motion not only causes the blocked control bars 61 to punch holes through the tape but moves such vanes 132 as are not blocked by the spacing bars 62, into the path of paper feed pawl 133.

The cam 110 causes feed lever 111 to swing about its pivot 112 to move feed pawl 133 along guide rod 134 axially along the tape until it is blocked by a feed vane 132. As the rotation of cam 110 continues the motion of feed lever 111 reverses, the feed pawl 133 picks up the tape and advances it an amount determined by the one of the spacing bars 62 which was blocked by the L-shaped bar 53.

In order to expedite the feeding of a new tape through the machine, rod 140 may be rocked about the axis of the trip rod 106 by pressing but-

ton 145. This rotates sleeve 141 and causes connecting rod 142 to release clutch 108. Each such operation will advance the paper tape ten element spaces, since in such operation, one of the feed selector vanes 132 is effective to stop the feed selector pawl 133.

While I have illustrated a particular embodiment of the present invention, it should be clearly understood that it is not limited thereto since many modifications may be made in the several elements employed and in their arrangement and it is therefore contemplated by the appended claims to cover any such modifications as fall within the spirit and scope of the invention.

What is claimed is:

1. A device for converting five unit code signals into telegraph code including a set of permutation bars, one individual to each element of the received code signal, means for selectively positioning each of said permutation bars in either of two positions in accordance with received signals, a case shift bar arranged with said permutation bars, a spring biased toggle member adapted to be selectively positioned in accordance with case shift signals set up on said permutation bars to shift said case shift bar and to maintain the same in its selected position pending receipt of a different case shift signal, a tape perforator including a set of perforator control bars arranged in parallel relationship to said permutation bars, said perforator control bars including perforating bars and spacing bars, a number of cross bars, two of said cross bars being selected by the positioning of said permutation bars for each different character to be converted, one of said two selected cross bars being selected by the position of said case shift bar, a number of L bars, one associated with each cross bar, said L bars being so arranged that each will block said perforating bars and spacing bars to condition said perforator to punch said tape in a pattern representative of a code character, said cross bars being normally held out of engagement with said permutation bars by a main bail, means for so actuating said main bail as to bring said cross bars into engagement with said permutation bars at the end of each received code signal, said L bars being so coupled to said cross bars that said cross bars may be lifted by said main bail without disturbing the selection of said perforator control bars by the selected one of said L bars, and means responsive to the completion of each perforating operation for restoring said perforator control bars and releasing said one L bar.

2. A device for converting five unit code signals into telegraph code including a set of permutation bars, one individual to each element of the received code signal, means for selectively positioning each of said permutation bars in either of two positions in accordance with received signals, a case shift bar arranged with said permutation bars, a tape perforator including a set of perforator control bars arranged in parallel relationship to said permutation bars, said perforator control bars including perforating bars and spacing bars, a number of cross bars, case shift cross bars arranged with said cross bars so that one of said case shift cross bars will be positioned selectively in accordance with the arrangement of said permutation bars in response to received case shift signals, a spring biased toggle member adapted to position said case shift bar in accordance with the positioning of said case shift cross bars and to maintain said case shift bar in position pending receipt of a case shift reversing signal.

5. A device for converting five unit code signals into telegraph code including a set of permutation bars, one individual to each element of the received code signal, means for selectively positioning each of said permutation bars in either of two positions in accordance with received signals, a case shift bar arranged with said permutation bars, a spring biased toggle member adapted to position said case shift bar in accordance with the positioning of said case shift cross bars, a sword and lever mechanism for selectively positioning each of said permutation bars in either of two positions in accordance with received signals, a set of

10. A device for converting five unit code signals into telegraph code including a set of permutation bars, one individual to each element of the received code signal, means for selectively positioning each of said permutation bars in either of two positions in accordance with received signals, a case shift bar arranged with said permutation bars, a tape perforator including a set of perforator control bars arranged in parallel relationship to said permutation bars, said perforator control bars including perforating bars and spacing bars, a number of cross bars, case shift cross bars arranged with said cross bars so that one of said case shift cross bars will be positioned selectively in accordance with the arrangement of said permutation bars in response to received case shift signals, a spring biased toggle member adapted to position said case shift bar in accordance with the positioning of said case shift cross bars and to maintain said case shift bar in position pending receipt of a case shift reversing signal, one of said cross bars being selected by the positioning of said permutation and case shift bars for each different character to be converted, a number of L bars, one associated with each cross bar, said L bars being so arranged that each will block said perforating bars and spacing bars to condition said perforator to punch said tape in a pattern representative of a code character, said cross bars being normally held out of engagement with said permutation bars by a main bail, means for so actuating said main bail as to bring said cross bars into engagement with said permutation bars at the end of each received code signal, said L bars being so coupled to said cross bars that said cross bars may be lifted by said main bail without disturbing the selection of said perforator control bars by the selected one of said L bars, and means responsive to the completion of each perforating operation for restoring said perforator control bars and releasing the said one L bar.

15. A device for converting five unit code signals into telegraph code including a set of permutation bars, one individual to each element of the received code signal, means for selectively positioning each of said permutation bars in either of two positions in accordance with received signals, a case shift bar arranged with said permutation bars, a tape perforator including a set of perforator control bars arranged in parallel relationship to said permutation bars, said perforator control bars including perforating bars and spacing bars, a number of cross bars, case shift cross bars arranged with said cross bars so that one of said case shift cross bars will be positioned selectively in accordance with the arrangement of said permutation bars in response to received case shift signals, a spring biased toggle member adapted to position said case shift bar in accordance with the positioning of said case shift cross bars and to maintain said case shift bar in position pending receipt of a case shift reversing signal, one of said cross bars being selected by the positioning of said permutation and case shift bars for each different character to be converted, a number of L bars, one associated with each cross bar, said L bars being so arranged that each will block said perforating bars and spacing bars to condition said perforator to punch said tape in a pattern representative of a code character, said cross bars being normally held out of engagement with said permutation bars by a main bail, means for so actuating said main bail as to bring said cross bars into engagement with said permutation bars at the end of each received code signal, said L bars being so coupled to said cross bars that said cross bars may be lifted by said main bail without disturbing the selection of said perforator control bars by the selected one of said L bars, and means responsive to the completion of each perforating operation for restoring said perforator control bars and releasing the said one L bar, and a tape advancing mechanism to advance said tape a predetermined distance without disturbing the operation of said selector mechanism.

20. A device for converting five unit code signals into telegraph code having in combination a set of permutation bars, one individual to each element of a received code signal, a sword and lever mechanism for selectively positioning each of said permutation bars in either of two positions in accordance with received signals, a set of

perforator control bars arranged in parallel relationship to said permutation bars, said perforator control bars including perforating bars and spacing bars, a number of cooperating cross bars and L bars, one set for each different character to be converted, said cooperating cross and L bars being arranged with respect to said permutation and said perforator control bars so that two of said cooperating bars are selected by the positioning of said permutation bars in response to each character signal received, a case shift bar arranged with said permutation bars, and a toggle member arranged to be selectively shifted to either of two positions in response to the positioning of said permutation bars by case shift signals to selectively position and hold said case shift bar pending receipt of a different case shift signal, whereby said case shift bar serves to select one of said two additional bars, and said selected one additional bar acts to block selected perforating bars to perforate a tape and acts to block a spacing bar to control the advance of said tape.

5. A device for translating received fixed unit code signals into telegraph code signals, including a set of permutation bars, one individual to each element of the received code signals, a further case shift permutation bar, means for selectively positioning each of said permutation bars in either of two positions in accordance with received signals, two case shift signal bars arranged in cooperative association with said permutation bars, said permutation bars selecting one of said case shift signal bars upon receipt of a case shift signal, a toggle lever arranged in cooperative relationship to said case shift signal bars to be actuated to either of two positions in accordance with the one of said case shift signal bars selected to selectively position said further case shift permutation bar in either of two positions corresponding to upper and lower case characters as expressed in said fixed unit code, a set of perforator control bars arranged in fixed relationship to said permutation bars, said control bars including perforating and spacing bars, a number of additional bars, one for each different character to be translated, arranged in cooperative relationship with said permutation bars

and said control bars, one only of said additional bars being selected by said permutation bars to block selected perforating bars and a selected spacing bar to control perforation and advance of a tape.

6. A device for translating received fixed unit code signals into telegraph code signals, including a set of permutation bars, one individual to each element of the received code signals, a further case shift permutation bar, means for selectively positioning each of said permutation bars in either of two positions in accordance with received signals, two case shift signal bars arranged in cooperative association with said permutation bars, said permutation bars selecting one of said case shift signal bars upon receipt of a case shift signal, a spring biased toggle lever arranged in cooperative relationship to said case shift signal bars to be actuated in accordance with the one of said case shift signal bars selected to selectively translate and hold said further case shift permutation bar in either of two positions corresponding to upper and lower case characters as expressed in said fixed unit code, a set of perforator control bars arranged in fixed relationship to said permutation bars, said control bars including perforating and spacing bars, a number of additional bars, one for each different character to be translated, arranged in cooperative relationship with said permutation bars and said control bars, one only of said additional bars being selected by said permutation bars to block selected perforating bars and a selected spacing bar to control perforation and advance of a tape.
